STARTING AND OPERATING CIRCUITS FOR FLUORESCENT LAMPS

William S. H. Hamilton, Larchmont, N. Y.

Original application February 15, 1950, Serial No. 144,345. Divided and this application November 28, 1952, Serial No. 322,872

3 Claims. (Cl. 315—103)

This application is a division of my prior application Serial No. 144,345, filed February 15, 1950.

This invention relates to improvements in starting and operating circuits for fluorescent lamps, particularly those operated on 60-volt and 110-volt D. C. and A. C. sources of current supply, such as lamps of the 12", T-8 (1 dia.), 15", T-12 (1½ dia.), 18", T-12 (1½ dia.) and 24", T-12 (1½ dia.) types, but which are adapted for use in connection with other hot-cathode lamps having like operating characteristics.

One object of the invention is to provide a novel and improved circuit organization employing a thermo-electromagnetic starter, preferably but not necessarily of plug-in type, for supplying preheating and operating currents to the lamp in such a manner as to secure quick starting and restarting actions.

Another object of the invention is to provide a starter embodying a time delay thermostatic switch and a relay embodying a switch member operating in conjunction therewith to preheat the lamp and to stop the preheating action and start the lamp as soon as it is sufficiently heated to fire.

Still another object of the invention is to provide a starter of the described type which will permit of a practically instantaneous restarting of the lamp which has been turned off and then turned on again shortly, regardless of the position of the thermal switch.

Still another object of the invention is to provide a starter of the type described in which a thermal switch and a relay are so compactly constructed, combined and arranged for use as to adapt the same to be enclosed in a plug-in "can" or casing of the same or practically the same size as that of a conventional starter, such as the FS-44 starter, and used in the same or a similar socket with little or no circuit wiring changes.

With these and other objects in view, which will appear in the course of the subjoined description, the invention consists of the novel features of construction, combination and arrangements of parts hereinafter more fully set forth, and as shown in the accompanying drawings, in which:

Figure 1 is a schematic diagram of one form of circuit as adapted for operation with a D. C. fluorescent lamp and employing a thermo-electro-magnetic starter embodying my invention, showing the parts in normal starting position.

Figure 2 shows an enlarged detail view of the circuit disclosed in Figure 1, showing the starter switches as arranged when the lamp is operating.

Referring now particularly to the drawings, 1 represents the gas containing envelope of the lamp having the negative cathode and positive filamentary electrodes 2 and 3, respectively, at least one of which is adapted to be preheated to start the lamp. In the case of a circuit as shown, which is designed to operate primarily on D. C., it is only necessary to heat the negative cathode filament, so that the positive filament is short circuited. Connected with these electrodes are operating conduc-

2

tors or leads 4a and 5a forming with the electrodes an operating circuit, which conductors are adapted to be connected at points 6 and 7 to the terminals of a line circuit adapted to be opened and closed in practice by suitable means. In the conductor 4a between the electrode 3 and terminal 6 are arranged a reactance 8a and a ballast lamp 9, which may be of any suitable type, and located in the output conductor 5a is the coil 10a of the relay of the combined thermal and relay switch device, hereinafter described.

Extending from the conductor 4a at a point between the reactance 8a and the lamp is a preheating conductor comprising input and output sections 11a and 12a and an intermediate switch circuit branch 13. A relay switch 14 normally connects through its contacts 15a, 15'a the output end of section 11a with the input end of section 12a and in the output end of branch 13a is a heating resistance 19a. An arc suppressing condenser 20' extends across the adjacent ends of sections 13 and 13a to suppress or reduce the arcing at the contacts 15a, 15'a of the relay switch when breaking the circuit through the reactance 8a. Connected in conductor 5a at opposite sides of the coil are connections 21 of a shunt circuit normally closed by the contacts 17a, 17'a of a second relay switch 16a and the contacts 22 of a thermostatic time delay means controlled by the heater 19a. Coil 10a is arranged to be shunted out of the path of flow of the preheating current when the switches are closed but so as to be connected into the preheating circuit when switch 22 opens and energized by preheating current to open switches 14a, 16a.

The conductors 11a, 12a, and switches 14a, 16a, 22 and connections 21 form the component parts of a preheating circuit of the starter which governs the flow of preheating current to the lamp. Normally the switches are closed as shown to coercively establish a preheating circuit to preheat the filament when the line circuit is closed for a starting action, which preheating circuit is automatically broken by contacts 15a, 15'a when the filament 2 is sufficiently heated, by the opening of the contacts 22 of the thermostatic time delay switch, which causes preheating current to energize coil 10a and open its contacts 15a, 15'a and 17a, 17'a. Breaking of the preheating circuit by switch member 14a causes the lamp if in good condition to fire and establish the operating circuit in which current flows from terminal 6 of the line, through the reactance 8a, ballast lamp 9a, conductor 4a to the positive filament 3 of the fluorescent lamp, through the gas in the lamp to filament 2, through conductor 5a, through coil 10a to conductor 5a and thence back to the negative terminal 7 of the line. The operating current flowing through coil 10a keeps it energized and both relay switches 14a and 16a open. The contacts 22 of the thermostatic time delay switch reclose upon cooling of heater 19a but their closure does not affect the operation since they cannot reclose the short circuit around the coil 10a due to the contacts 17a, 17'a of switch 16a being open. Thus the lamp will continue to operate so long as the line circuit is closed and upon its being opened, switches 14a and 16a will immediately reclose so as to be ready for another starting action as soon as the line circuit is reclosed.

In practice the switch elements and their coating members are preferably arranged as an assembly so aligned that they may be disposed in close compass and so as to be enclosed within a "can" or plug-in container casing as indicated in dotted lines at 26, said casing having plug-in prongs or contacts C, D, E, F to fit within a receiving socket for connection with the associated conductors. The arrangement of the parts comprising the starter may, in fact, be such as to provide a unitary starter of the type shown in my aforesaid application, Ser. No. 144,345, or

any other suitable type of unitary starter adapted to fit within a can of the same size as the can of the well known FS-44 starter. By this means a combined thermostatic switch and relay starter embodying my invention may be used in connection with installed lamps of the types described and other similar types with little or no rewiring. A further advantage of this structure is that, if mounted in an FS-44 starter socket, it will be reversible as to position, as said shocket is so arranged by the size of its openings to receive the prongs of the starter in only two positions, either of which gives proper operation of the circuit.

The parts are normally arranged as shown in Fig. 1 to establish the starting circuit to supply preheating current to the lamp when the line circuit is closed.

It is to be understood that in the circuit organization shown the positive filament may be short-circuited or left open-circuited depending on the characteristics of the particular lamp used in the circuits.

It is also to be understood that while, for convenience in use, the switches and their connections are preferably placed in a starter can, which gives practical advantages, these parts, within the scope of my invention, may be placed partly within and partly without the can. It is also to be understood that while the circuit organizations are shown for example as being designed for use in connection with D. C. lamps, they may with little or no changes or suitable changes be used in connection with A. C. lamps.

Having thus described my invention, I claim:

1. In a system for supplying preheating and operating current to an electric discharge device having at least one filamentary electrode, an electromagnetic switch comprising two normally closed contact means and an operating winding, a thermal switch comprising normally closed contacts and an operating heater, means including an inductance ballast and said winding for connecting said electrodes with a source of current supply, a preheating circuit capable of producing firing temperature electrode heating connected across said device, said circuit including in series connection the electrode which

is to be preheated, the first of said contact means, the said heater and the winding of said electromagnetic switch, and a circuit in shunt around said winding and including in series connection said thermal switch and the second of said contact means so that when said thermal switch opens it introduces said winding into the said preheating circuit causing operation of said electromagnetic switch, the opening of the first contacts thereof breaking the preheating circuit rapidly and causing the discharge device to fire by an induced voltage produced by said ballast and maintaining the preheating circuit open and the heater of said thermal switch cut off during the operation of the discharge device.

2. A system for supplying preheating and operating current to an electric discharge device as claimed in claim 1 in which the first contact means of the electromagnetic switch and the heater of the thermal switch are connected in series between one side of the supply source and one terminal of the electrode to be heated, the opposite terminal of said electrode being connected to the opposite side of the supply source through the winding of the electromagnetic switch.

3. In a starting device for electric discharge lamps having at least one filamentary electrode, the combination comprising an electromagnetic switch having an operating winding and two normally closed contact means, one of which is included in a shunt circuit across said winding, a thermal switch having normally closed contacts included in said shunt circuit, and a heater located to actuate said contacts to open position when heated and connected in series with the second of said normally closed contact means of said electromagnetic switch, and preheating circuit means including in series connection the electrode to be preheated, said heater and both of said normally closed contact means.
